(57) **CLAIM**

The ornamental design for a card case, as shown and described.

DESCRIPTION

FIG. 1 is a front, top and left side perspective view of a first embodiment of a card case, showing my new design in an open configuration;

FIG. 2 shows the card case from FIG. 1 in a folded configuration;

FIG. 3 shows the card case from FIG. 1 in a closed configuration;

FIG. 4 is a front view of FIG. 1 thereof;

FIG. 5 is a rear view of FIG. 1 thereof;

FIG. 6 is a left side view of FIG. 1 thereof;

FIG. 7 is a right side view of FIG. 1 thereof;

FIG. 8 is a top view of FIG. 1 thereof;

FIG. 9 is a bottom view of FIG. 1 thereof;

FIG. 10 is a front, top and right side perspective view of a second embodiment of a card case showing my new design in an open configuration;

FIG. 11 shows the card case from FIG. 10 in a closed configuration;

FIG. 12 is a front view of FIG. 10 thereof;

FIG. 13 is a rear view of FIG. 10 thereof;

FIG. 14 is a left side view of FIG. 10 thereof;

FIG. 15 is a right side of FIG. 10 view thereof;

FIG. 16 is a top view of FIG. 10 thereof; and,

FIG. 17 is a bottom view of FIG. 10.
